CORRUGATED STEEL FLOOR FOR
REFRIGERATOR CARSEdwin R. Battley and George E. McCoy,
Montreal, Quebec, Canada

Application January 26, 1945, Serial No. 574,792

6 Claims. (Cl. 105—422)

1

Our invention relates to railway refrigerator cars such as are used to transport perishable edible commodities, and more particularly to the floor construction thereof, and has for its object to provide a strong and light construction, easy to manufacture and build into a car of this type.

The floor is particularly adaptable to cars known in the trade as overhead bunker cars, wherein air is cooled by being forced to circulate around said bunkers, down through flues associated with the side walls of the car, and up through the lading compartment about the lading therein. The floor is also adapted for use in such cars when crushed ice is placed directly upon the lading and wherein the water from the melting ice drains down over and about the lading to the floor beneath and is directed thereby out of the car.

An object of the invention is to secure a relatively thin corrugated sheet to the sub-floor, under the foraminous floor, which sheet performs the double function of strengthening the floor, and the corrugations provide transverse flues to more evenly distribute the cooled air under the lading so as to evenly cool said lading, and wherein said corrugations also provide transverse troughs to direct water to the sides of the car floor.

A further object of the invention is to secure said corrugated metallic sheet at its side and end edges to the sides and ends of the car so that moisture may not penetrate therethrough to the car insulation.

Still another object of the invention is to provide a corrugated floor sheet to support the foraminous floor.

Other objects and advantages of the invention will appear in the following description thereof.

Referring now to the accompanying drawings forming part of this application and wherein like reference characters indicate like parts:

Figure 1 shows a vertical section through a lower corner of a refrigerator car and floor illustrating the corrugations as terminating within the sheet to form a flat margin and a flange overlapped by the flue sheet and supported by the bottom chord of inner truss and with longitudinal perforated stringers upon the corrugated sheet for supporting the foraminous floor.

Figure 2 is a similar view showing the foraminous floor resting directly upon the corrugated floor sheet, but wherein the floor sheet overlaps one side wall of a gutter, and the flue sheet overlaps the other side wall of said gutter.

Figure 3 is a view similar to Figure 2, but wherein the inner wall of the gutter is provided with a scalloped upper edge which is overlapped by the corrugated sheet, the corrugations extending to the edge of the sheet for this purpose.

2

Figure 4 is a perspective view, partly broken away, of Figure 3.

In the drawings, the floor of the car is shown as comprising the lower metallic sheet 1, plies of insulating material 2, wooden sub-floor 3, and corrugated metallic floor sheet 4. In Figure 1 the corrugations 5 are shown as terminating within the sheet, providing a flat side marginal portion 6 which, at its outer edges, is turned upwardly at an angle providing a flange 7, thereby forming a gutter extending longitudinally of the car.

The side wall comprises the outer sheathing 8 attached in any acceptable manner at its lower edge to a vertical arm 9 of the side sill 10. Longitudinally spaced inner side posts 11 (Fig. 4) rests upon the floor 3 and a flue sheet or sheets 12 extend between said posts to provide flues 13 for conducting cooled air from the upper part of the car to the space 14 adjacent the floor. Plies of insulating material 15 are installed between the outer sheathing 8 and flue sheet 12 to prevent egress or ingress of heat through said wall. An inner side sill 16 or bottom chord member, is shown as comprising an angle having a vertically disposed arm 17 secured to said posts, as by rivets 18, and a horizontally disposed arm 19 supporting the ends of the corrugations so that at least part of the load imposed on the corrugations is carried thereby to said chord member. The chord member 16 is supported by a timber or beam 20 directly therebelow. The lower edge of the flue sheet 12 is provided with a downwardly and inwardly extending flange 23 which overlaps the flange 7 and is secured thereto by a line of welding 24. Thus the floor and flue sheets adequately prevent any moisture from contacting the insulation material. Flue lining is shown at 25 so that air and liquid flow downwardly therethrough and out into the space 14 adjacent the car floor, as shown by the arrows, Figure 1. Longitudinal stringers are shown at 26 as resting upon the corrugations 5, which stringers support the foraminous floor 27 upon which the lading is carried.

Stringers 26 are provided with perforations 28 through which the air may circulate and the foraminous floor 27 is provided with a plurality of spaced holes 29 so that the circulating air, as it passes under the foraminous floor, is warmed by the lading and may pass upwardly through said holes 29 to and about the lading. The spaces between the floor 27 and floor sheet 4 intermediate the corrugations 5 provide a plurality of transverse channels within which the air may move in its circulating path. Also when the foraminous floor 27 is removed for cleaning the corrugated sheet, as with a hose, the water is carried to the gutter by said channels.

In Figure 2 the corrugated floor sheet 30 is similar to that shown in Figure 1, excepting that a

channel-shaped gutter 31 is provided having an inner side wall 32 formed with a flange 33, and thus the side margin 34 of the floor sheet is turned downwardly overlapping the flange 33 and side wall 32 and may be secured thereto in any acceptable manner. The corrugations 35 in this modification merge into the flange 34 and the ends of said corrugations are supported by the gutter 31. The inner side sill is shown at 36 and the outer wall 37 of the gutter abuts against the vertical arm of said sill 36. In this modification the lower margin 38 of the flue sheet 39 overlaps the outer wall 37 of the gutter, thereby carrying any drainage from said flues directly to the gutter and thence out of the car through usual drains indicated at 40.

Because the gutter provides additional area at the juncture of the flue 13 and space 41 under the floor 42, said floor may rest directly upon the corrugations 35 of the floor sheet and still provide room for the circulating air thereunder.

In Figures 3 and 4 the corrugations 45 of the floor sheet 46 extend to the edge of the sheet. The inner wall 47 of the gutter 48 is provided with a serrated upper edge, as clearly shown in Figure 4, said serrations snugly fitting the under surface of the corrugated floor sheet 46 to thereby close the space under said corrugations. The foraminous floor 49 in this instance also rests directly upon the corrugations 45, the outer plank 50 thereof extending over the side of the gutter and being supported by the spaced angle clips 51 secured, as by rivets 52, to the side wall 47 of the gutter. The remainder of the structure is substantially identical with that shown in Figure 2.

It will be noted in Figure 4 that a corrugation 45 of the floor sheet 46 occurs opposite each post 11 so that the flues 13 between said posts are thereby positioned opposite the space between the corrugations 45 opposite the posts. Furthermore the cross sectional area of the flues 13 is substantially equal to the cross sectional area of the spaces between the corrugations and under the foraminous floor 49 so that there is no choking of the air circulation as it passes from the flues to the space between said corrugations.

While the corrugations 45 are shown in Figure 4 as being spaced, it is obvious that they may be sinuous and so proportioned as to function as above set forth.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

We claim:

1. In a railway refrigerator car floor, a substantially channel-shaped gutter, a floor sheet overlapping one wall of said gutter and secured thereto, said floor sheet having corrugations formed therein extending at substantially right angles to said gutter, and a foraminous floor resting upon the apices of said corrugations and supported by said corrugations, whereby said corrugated floor sheet strengthens said floor and divides the space between said sheet and foraminous floor into a plurality of channels to evenly distribute air circulating therethrough.

2. In a railway refrigerator car floor, a substantially channel-shaped gutter extending longitudinally of the car, a floor sheet overlapping one wall of said gutter and secured thereto, said floor sheet having corrugations formed therein ex-

tending substantially transversely of said car, and a foraminous floor resting upon the apices of said corrugations and supported by said corrugations, whereby said corrugated floor sheet strengthens said floor, supports said foraminous floor and divides the space between said sheet and foraminous floor into a plurality of channels to evenly distribute air circulating therethrough.

3. In a railway refrigerator car floor, a substantially channel-shaped gutter having the upper edge of one wall thereof serrated, a floor sheet overlapping the serrated wall of said gutter and secured thereto, said floor sheet having corrugations formed therein extending to the edge of said sheet, said serrations conforming to the shape of the under side of the edge of said sheet, and a foraminous floor resting upon and supported by said corrugations.

4. In a railway refrigerator car having a wall and vertical air flues associated therewith and a floor; said floor including a floor sheet formed with a plurality of corrugations extending normal to said wall, and a foraminous floor resting upon the apices of said corrugations and supported by said corrugations to provide air circulating spaces between said corrugations, whereby air descending through said flues into said spaces is distributed through said foraminous floor to a lading carried thereby.

5. In a railway refrigerator car having a wall and vertical air flues associated therewith and a floor; a substantially channel-shaped gutter at the juncture of said wall and floor, said floor including a floor sheet overlapping one wall of said gutter and formed with a plurality of corrugations extending normal to said gutter, and a foraminous floor resting upon the apices of said corrugations and supported by said corrugations to provide air circulating spaces between said corrugations, whereby air descending through said flues into said spaces is distributed through said foraminous floor to a lading carried thereby and liquid descending through said flues and liquid upon said corrugated sheet is drained into said gutter.

6. In a railway refrigerator car having a wall comprising spaced posts and vertical air flues therebetween and a floor; a substantially channel shaped gutter at the juncture of said wall and floor; said floor including a floor sheet overlapping one wall of said gutter and formed with a plurality of corrugations extending normal to said gutter, and a foraminous floor resting upon the apices of said corrugations and supported by said corrugations to provide air circulating spaces between said corrugations, whereby air descending through said flues into said spaces is distributed through said foraminous floor to a lading carried thereby, the area of said spaces being substantially equal to the area of said flues.
